CLAIM

The ornamental design for a bubble-making toy as shown and described.

DESCRIPTION

1.1 : Top

1.2 : Bottom

1.3 : Front

1.4 : Right

1.5 : Perspective

1.6 : Exploded

The product is a bubble-making toy to make soap bubbles; the design results from the shape and patterns of the product as represented in the annexed drawings, which is best illustrated in front perspective view of fig 1.5; the views are as follows: **1.1** Top view, **1.2** Bottom view, **1.3** Front view, **1.4** Right view, **1.5** Perspective (front, top, right) view, **1.6** Exploded (front, top, right) view; the back view is omitted because it is identical to the front view; the left view is omitted because it is identical to the right view.
